UNITED STATES PATENT OFFICE.

FRANK L. WHITE, OF TOPEKA, KANSAS.

FLUSHING-VALVE.

1,230,634.

Specification of Letters Patent. Patented June 19, 1917.

Application filed April 27, 1916. Serial No. 93,932.

To all whom it may concern:

Be it known that I, FRANK L. WHITE, a citizen of the United States, residing at Topeka, in the county of Shawnee and State of Kansas, have invented certain new and useful Improvements in Flushing-Valves; and I do hereby declare the following to be a full, clear, and exact description of the invention, such as will enable others skilled in the art to which it appertains to make and use the same:

This invention contemplates improvements in that type of flushing valve consisting of a hollow body, formed of rubber, and located in the flushing tank of a closet, and seated on a metallic seat, the said valve being adapted to rise to the surface of the water within the tank, when relieved from the pressure of the water, so as to admit of discharge of the water through the pipe which communicates the tank and the closet bowl, the said valve having a guide rod thereon which is operable through a guide arm removably carried by the overflow pipe located within the tank, the said overflow pipe being in turn detachably connected to the discharge pipe which communicates the tank and the closet bowl. It has been found that after a very short period of use, the rubber valve gets out of shape and the metallic seat corrodes, thereby preventing accurate seating of the valve on the seat, and causing leakage through the discharge pipe; and further during the repeated operations of the valve, the overflow pipe and the guide arm carried thereby will work loose, resulting in the valve being moved out of alignment with the seat.

The object of this invention is to overcome all of the foregoing disadvantages by integrally connecting the overflow pipe and the guide arm and also integrally connecting the overflow pipe with the discharge pipe, and substituting for the rubber valve a hollow brass body, formed of light casting, and having removably associated therewith, a novel type of rubber seat, which normally rests on a novel type of seat detachably mounted on the discharge pipe, and formed preferably of porcelain so as not to corrode.

Other objects will appear and be better understood from that embodiment of my invention of which the following is a specification, reference being had to the accompany-

ing drawing forming a part thereof, in 55 which:

Figure 1 is a vertical sectional view taken through the discharge pipe, valve and overflow pipe;

Fig. 2 is a top plan view of the discharge pipe with the valve removed, and

Fig. 3 is a perspective view of the valve seat detached from operative position.

Referring to the drawing in detail, the numeral 1 designates a discharge pipe adapted to extend through the bottom wall of a flush tank (not shown), and to have its lower end connected up with the closet bowl (not shown). Located to one side of the upper or inner end of the pipe 1 is a vertically disposed overflow pipe 2, which has its lower end extended toward the pipe 1 and integrally secured thereto and has its interior thereof communicating with the interior of the pipe 1, as shown in Fig. 1. The upper end of the overflow pipe 2 extends a considerable distance above the upper end of the pipe 1 and is provided, against its upper terminal, with a laterally extending guide arm 3, which is integrally formed with the pipe 2 and overlies the pipe 1. By virtue of forming the overflow pipe 2 integral with the pipe 1, and the guide arm 3 integral with the overflow pipe 2, the said pipe 2 and arm 3 will be held against movement so that the guide arm 3 will always be disposed in alignment with the pipe 1.

A removable body 4 is mounted on the upper end of the pipe 1 and is formed of porcelain, or similar material, and has a depending portion 5 extending into the interior of the pipe 1. The body 4 is provided with a central bore 6, and the upper end of the body is beveled as shown at 7, to provide a valve seat. An angular shoulder 8 is formed on the body 4 and overlies the upper end of the pipe 1, which upper end is thickened, as shown at 9, and interposed between the upper end of the pipe 1 and the shoulder 8, is a rubber gasket 10 designed to prevent leakage between the body 4 and the upper end of the pipe 1.

The upper end of the pipe 1 is threaded, as shown at 11, and has turned thereon a nut 12 which has an angular flange 13 formed on the upper side thereof and which engages over the shoulder 8 on the body 4 so as to hold the body 4 in position and

also to provide a tight joint between the pipe 1 and the body 4.

The flushing valve is designated as an entirety, by the numeral 14 and consists of a hollow body formed of brass, and consisting of an upper semi-spherical shaped portion 15 and a lower substantially inverted frusto-conical shaped portion 16, the lower end of the body being closed by means of a wall 17. A threaded lug 18 depends from the under side of the wall 17 and is threadedly received by a bore formed in a rubber body 19, which forms a seating face for the valve. The body 19 has the opposite sides thereof provided with beveled portions 20 and 21, the portion 21 being shown as engag- 10 ing the seat 7, but the body 19 is reversible so that the portion 20 can be presented to the seat 7 when the portion 21 becomes worn. 15 A suitable locking nut 22 is turned on the lower end of the lug 18 and is adjustable against the under side of the body 19 so as to hold the body in position.

A diametrically extending rod 23 is positioned within the pipe 1, at a point below the upper end thereof, and is centrally provided with an opening which slidably receives the lower end of a rod 24, the upper end of the rod being threaded for reception 25 by a bore 25 formed in the lug 18.

The guide stem 26 is slidable through an opening in the free end of the guide arm 3 and has its lower end threaded for reception 30 by an opening in the upper end of the valve body, the upper end of the stem being terminally provided with a spherical end 27, which is removable therefrom. The upper

end of the overflow pipe 2 adjustably receives the pipe section 28, which admits of the overflow pipe being lengthened as desired, to accommodate tanks of different depths, the section being held in adjusted position by means of a flanged collar 29, which has an opening therein which frictionally receives the pipe section 28, and a gasket 30 is interposed between the collar and the upper end of the pipe section 28 so as to prevent leakage between the overflow pipe and the pipe section 28.

It will of course be understood that various minor changes in the detail of construction can be had without departing from the spirit of the invention as claimed.

Having thus described my invention, what I claim as new is:—

In a flushing device, the combination with a discharge pipe and a flushing valve, of a non-metallic body located at one end of said discharge pipe and having a valve seat formed thereon to be engaged by the valve, 55 an annular shoulder formed on the body and overlying the adjacent end of the pipe, a gasket interposed between the shoulder and the pipe, a nut threaded on the mentioned end of the discharge pipe, and an annular 60 flange formed on the nut engaging over the shoulder on the body.

In testimony whereof I affix my signature in presence of two witnesses.

FRANK L. WHITE.
